UNITED STATES PATENT OFFICE.

HOWARD C. BUSWELL, OF JEFFERSON, IOWA.

ANTISUBLUXATION DEVICE.

1,294,393.

Specification of Letters Patent.

Patented Feb. 18, 1919.

Application filed August 15, 1917. Serial No. 186,393.

To all whom it may concern:

Be it known that I, HOWARD C. BUSWELL, a citizen of the United States, and a resident of Jefferson, in the county of Greene and State of Iowa, have invented a certain new and useful Improvement in Antisubluxation Devices, of which the following is a specification.

The present invention relates to a device for correcting the subluxation of vertebrae, such as frequently found in the spinal column.

It is well known to those skilled in the art that the spinal column is made up chiefly of twenty-four vertebrae between which are interposed twenty-three intervertebral cartilages and various nerves, and that many prolonged diseases or disorders of the human body directly attributable to the subluxation of the vertebrae, or, in other words, to the moving of the vertebrae out of their normal axis.

Such defects in the spinal column have been corrected by exerting sudden impacts against the dislocated member and snapping the same into its correct position. This release, however, is very often only temporary as there is nothing that holds the subluxated vertebra in its correct position until the cartilages and the muscles are sufficiently set to permanently correct the subluxation.

The object of the present invention, therefore, is to provide a device for application to the spinal column for moving the subluxated member back into its correct position, and for holding said member in such position until the cartilages and the nerves assume their normal and natural proportions and positions to retain the subluxated member permanently in its correct position.

The present invention also embraces a structure embodying certain features of adjustment to adapt the device to various sizes of vertebrae and to the various spaced-apart positions of the same found in different spinal columns, thus providing a device which is adjustable and which is adapted for universal use.

The invention still further aims at the provision of a device for gradually moving the subluxated member into correct position so that violent or sudden impact is not required, and so that the members may be gradually returned into correct alinement without discomfort or pain to the patient.

The above, and various other objects and

advantages of this invention will be in part described, and in part understood, from the following detailed description of the present preferred embodiment, the same being illustrated in the accompanying drawing wherein:

Figure 1 is an outer side elevation of a device constructed according to the present invention.

Fig. 2 is a horizontal section through the same taken on a plane indicated by the line 2—2 of Fig. 1.

Fig. 3 is a vertical section taken substantially centrally through the device on a plane indicated by the line 3—3 in Fig. 1.

Fig. 4 is a detail view of the adjusting means employed.

In the drawing, 10 and 11 designate a pair of slightly arcuate plates which are held in suitably spaced-apart relation by a pair of adjustable screws 12 arranged at the opposite end portions of the plates. The plates 10 and 11 are provided intermediately with relatively large registering apertures 13, and the end portions of the outer plate 10 are curved inwardly at the concaved side of the plates on a smaller arc than the radius of curvature of the major portion of the plate. The inner plate 11 is curved outwardly at its end portions to lie flat thereat against the back. The end portions of the plates 10 and 11 form sockets into which are fitted rounded heads or balls 15.

Stems 16, threaded throughout their length, are threaded diametrically through the balls 15 and project at opposite ends through relatively wide vertically extending slots 17 formed in the inner and outer plates 10 and 11 in the socket portions thereof. The slots 17 formed in the outer plate 10 are spaced apart a greater distance relatively to the distance between the slots 17 in the inner plate 11, and the stems 16 converge inwardly toward each other at the convex side of the device, and the balls 15 project into the slots 17 for holding the balls from displacement.

Presser plates 18 are swiveled upon the inner ends of the stems 16 and are preferably relatively small, and may be of any suitable configuration. The presser plates 18 are preferably formed with concave abutting faces, and may be provided with a cover of felt or the like, as indicated at 19.

As shown in Figs. 1 and 3, one end of the device may be provided with a pair of the

presser members arranged near the top and bottom portions of the plates 10 and 11, and having the stems 16 thereof engaged in vertically extending superposed slots 17. The 5 presser members are adapted for movement toward and from each other in the slots 17 at said end of the device, and the adjustment is effected, and the members are held in suitable spaced apart relation, by the provision of a connecting rod 20 being oppositely threaded at its opposite ends and engaging in threaded relation through the upper and lower heads 15 of the presser members. The intermediate portion of the 10 rod 20 is provided with a knurled thumb nut 21 which fits in a recess 22 formed in the outer plate 10, and which may be turned for moving the pressure members toward and from each other.

15 At the opposite end of the device, a single pressure member is preferably employed, the same being located in a horizontal plane between the horizontal planes of the pair of spaced apart pressure members, and the stem 16 thereof engaging at opposite ends through the openings 23 which correspond to the slots 17.

20 The device is adapted to be supported against the back of the person by a belt or the like, and one means of retaining the device in position is illustrated in the accompanying drawing. In the present embodiment a preferably flexible sheet 24, of canvas, felt, rubber or other suitable material 25 or composition is fitted over the outer plate 10 and is provided with a relatively large opening 25 therein adapted to disclose the outer free ends of the stem 16 of the pressure members, the latter being curved, and 30 admitting access thereto for adjusting the stems longitudinally through the balls or heads 15. The plate 24 is provided at opposite ends with tongues 26 or the like upon which buckles 27 may be mounted, and suitable belt straps 28 may be secured through 35 the buckles as shown for binding the device against the back of the wearer. The covering 24 is held to the outer plate 10 by the provision of tabs 29 carried upon cover 24 and which engage through openings 30 formed in the upper and lower edge portions 40 of the plate 10, the tabs 29 being held in place by buckles 31 or the like which are carried upon the covering 24.

45 In use, the device is fitted against the back and against the spinal column. The pair of pressure members mounted upon one side of the device engages against an alternate pair of the vertebrae A of the spinal column, and 50 the single pressure member located intermediate of the pair of pressure members at the opposite end of the device engages against an intermediate spinous process subluxated vertebra B. When the device is 55 secured tight against the back of the patient,

the stems 16 are adjusted, the pair of stems at one side of the device to hold the vertebrae A in position, and the stems 16 of the single pressure member being adjusted to exert considerable pressure upon the distorted member B. The single presser foot 18 may be advanced from time to time to gradually urge and hold the distorted member B into correct position, the adjustment being effected without removing the device 70 or changing the location of the same. It is thus readily seen that the subluxation or deformity of the spinal column may be readily corrected, and permanently cured as the dislocated member B, is gradually moved 80 into correct position and held in that position until the muscles and cartilages set sufficiently for holding the parts in true alignment without the use of the device. The adjusting rod 20 moves the pair of pressure 85 members into correct registry with the alternate pairs of vertebrae A depending the spacing apart of the same. The spherical shape of the balls or heads 15, in connection with the slots in the plates through which 90 the stems 16 extend permit of a greater amplitude of adjustment of the pressure members and also of more minute and exact adjustment.

The device is relatively simple in construction, comprises few parts, and may be accurately adjusted to meet the varying conditions found in the correction of the spinal column.

It is of course understood that the above 100 specifically described device is only one embodiment of the present invention, and that various changes and modifications may be made in the details of construction and design of the device without departing from 105 the spirit of this invention; such changes and modifications being restricted only by the scope of the following claims.

I claim:—

1. In a device for the correction of subluxation of the spinal vertebrae, the combination of a support, means for securing the support against the back of the patient, pressure elements carried upon one end of the support for engagement against alternate spaced apart vertebrae, and a single pressure element carried upon the opposite end of the support for bearing against the intermediate dislocated vertebra, and means for simultaneously adjusting the position of 110 said first named pressure elements.
2. In a device for the correction of subluxation of the spinal vertebrae, a support, pressure members arranged at the opposite ends of the support and adapted for engagement against alternate and intermediate vertebrae, and means for advancing said pressure members toward and from the vertebrae when in position, and means for simultaneously adjusting the positions of 120 125 130

- the alternate vertebræ pressing members with respect to each other.
3. In a device for the correction of subluxation of the spinal vertebræ, the combination of a support, sockets formed in the opposite ends of the supports, balls mounted in said sockets, stems adjustably engaging through the balls and projecting inwardly from the support, pressure plates mounted on the inner ends of the stems and adapted for engagement against the spinal vertebræ, means for adjusting the balls at one end of the plate toward and from each other to register with spaced alternate vertebræ, the pressure member at the opposite end of the support being vertically offset from the adjustable pressure members.
4. In a device for the correction of subluxation of the spinal vertebræ, the combination of a pair of plates, means for retaining the plates in spaced-apart relation, said plates being formed with sockets between the opposite ends thereof, a pair of vertically spaced-apart balls mounted in the sockets at one end of the plates, stems threaded through the balls and adapted to project inwardly from the plates, pressure plates mounted on the inner ends of the stems, a single ball mounted in the socket between the opposite ends of the plate and in offset relation to the balls at said first ends of the plates, a stem threaded through the offset ball and projecting inwardly therefrom, a pressure plate upon the free end of said second stem, and means for holding the plates against the back of a patient with the pair of pressure plates against one side of the spinal column in register with alternate spaced vertebræ, and with the single pressure plate in register with an intermediate dislocated vertebra.
5. In a device for the correction of subluxation of the spinal vertebræ, a support, the combination of a support, a pair of pressure members mounted on one end of the support and including heads adjustable from and toward each other, a rod threaded in opposite directions at opposite ends engaging in threaded relation through said heads and having a finger engaging portion intermediate the ends of the rod to turn the same and move said pressure members toward and from each other, and a single pressure member mounted in the opposite end of the support in vertically offset relation to said pair of pressure members, said pressure members being adapted for adjustment to register with alternate and intermediate vertebræ of the spinal column.
6. In a device for the correction of subluxation of spinal vertebræ, a pair of vertebræ pressing members, carrying heads for said members, a rod having its end portions oppositely threaded and threadably engaging through said carrying heads whereby the heads will be moved in opposite directions upon rotation of the rod.
7. In a device for the correction of subluxation of spinal vertebræ, carrying heads, vertebræ pressing members adjustably carried by said heads, a rod having its end portions oppositely threaded and threadably engaging through said carrying heads whereby the heads will be moved in opposite directions upon rotation of the rod.
8. In a device for the correction of subluxation of the spinal vertebræ, supporting plates, carrying heads adjustably carried by said supporting plates, stems threaded through said carrying heads, vertebræ pressing members swivelly connected to said stems, a rod having its end portions oppositely threaded and threadably engaging through said carrying heads whereby the heads will be moved in opposite directions upon rotation of the rod.
9. In a device for the correction of subluxation of the spinal vertebræ, the combination of a pair of plates, means for retaining the plates in spaced apart relation, said plates being formed with sockets between the opposite ends thereof, a pair of vertically spaced apart balls mounted in the sockets at one end of the plates, stems threaded through said balls and adapted to project inwardly from the plates, pressure plates swivelly mounted on the inner ends of said stems, and means connecting said balls to simultaneously move them toward or from each other.
10. In a device for the correction of the subluxation of the spinal vertebræ, the combination of a support, means for securing the support against the back of the patient, pressure elements carried upon one end of the support for engagement against alternate spaced vertebræ, and means for simultaneously adjusting the position of said pressure elements.
11. In a device for the correction of the subluxation of the spinal vertebræ, vertebræ pressing members, a rod having its end portions oppositely threaded, and means connecting said rod and said pressing members whereby the members will be moved in opposite directions upon rotation of the rod.
12. In a device for the correction of the subluxation of the spinal vertebræ, the combination, of a support, means for retaining the support against the back of a patient, carrying heads carried by said support, vertebræ pressing members adjustably carried by said heads, a rod having its end portions oppositely threaded and threadably engaging through said carrying heads whereby the heads will be moved in opposite directions upon rotation of the rod.
13. In a device for the correction of the subluxation of the spinal vertebræ, the combination, of a support, means for retaining

- the support against the back of a patient, vertebræ pressing members adjustably carried by said support, a rod having its end portions oppositely threaded, means connecting said rod and said pressing members whereby the members will be moved in opposite directions upon the rotation of the rod, and a single pressing element carried by the support in opposed relation to the 10 first named pressing elements and intermediate them for bearing against the vertebræ intermediate of the vertebræ engaged by the first mentioned pressing members.
14. In a device for the correction of subluxation of the spinal vertebræ, the combination, of supporting plates provided with 15 slots, carrying heads adjustably carried by said supporting plates, stems threaded through said carrying heads and engaging in said slots, vertebræ pressing members swivelly connected to said stems, said slots acting as guides and limits for the adjusted movement of said spherical carrying heads and said stems.

in said slots, vertebræ pressing members 20 swivelly connected to said stems, a rod having its end portions oppositely threaded and threadably engaging through said carrying heads whereby the heads will be moved in opposite directions upon rotation 25 of the rod.

15. In a device for the correction of the subluxation of the spinal vertebræ, superposed supporting plates provided with a plurality of pairs of alining slots, spherical 30 carrying heads carried by said supporting plates, stems threaded through said carrying heads and engaging in said slots, vertebræ pressing members swivelly connected to said stems, said slots acting as guides and limits 35 for the adjusted movement of said spherical carrying heads and said stems.

HOWARD C. BUSWELL.
